UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A SHOE FOR PLOWS.

SPECIFICATION forming part of Design No. 32,125, dated January 23, 1900.

Application filed December 2, 1899. Serial No. 739,051. Term of patent 14 years.

To all whom it may concern:

Be it known that I, GEORGE W. REAM, a citizen of the United States, residing at Canton, in the county of Stark and State of Ohio, have 5 invented and produced a new and original Design for Shoes for Plows, of which the following is a specification.

In the accompanying drawings, Figure 1 represents in elevation the inner side of a 10 landside-shoe embodying my design. Fig. 2 is a plan of the same. Fig. 3 is an elevation of the outer side. Fig. 4 is a front view.

The invention is a shoe to support the landside of a plow, and the leading feature of the 15 design resides in the outline shape of the shoe.

A secondary feature is the surface configuration. As shown in Fig. 1, the inner face A of the shoe is substantially plain, except for a flange *a* on its lower edge. This part in- 20 creases slightly in width toward the front to the point *b*, and from thence the upper edge

inclines downwardly toward the front. A wing B projects from the inner face of the part A, extending rearwardly and also curving downwardly, as shown in Figs. 1, 2, and 25 4. The opposite face of the shoe is shown at C in Fig. 3, in which there are a series of recesses *c*, separated by vertical projections *d*. The wing B is made up of two surfaces, joining each other by a shoulder at *e*, but of different inclinations. From point *b* the upper edge of the shoe curves downwardly and merges into the upper straight edge of the shoe. 30

What I claim is—

The design for a shoe as herein shown and described.

GEORGE W. REAM.
